Primary Examiner — Darlington Ly(74) *Attorney, Agent, or Firm* — Doherty Wallace
Pillsbury & Murphy(57) **CLAIM**

The ornamental design for a chain ring bash guard, as shown and described.

DESCRIPTION

FIG. 1 is a front perspective view of a chain ring bash guard showing my new design;

FIG. 2 is a front elevation view thereof;

FIG. 3 is a bottom plan view thereof;

FIG. 4 is a top plan view thereof;

FIG. 5 is a side elevation view thereof; and,

FIG. 6 is a front elevation view thereof, wherein the chain ring bash guard is shown installed on a bicycle crankset. The broken line showing the bicycle crankset is provided for the purpose of illustrating environmental structure and forms no part of the claimed design.
